UNITED STATES PATENT OFFICE.

ADOLF DREYER, OF POTSDAM, GERMANY.

BOTTLE-CLOSURE.

No. 903,888.

Specification of Letters Patent.

Patented Nov. 10, 1908.

Application filed August 26, 1908. Serial No. 450,344.

To all whom it may concern:

Be it known that I, ADOLF DREYER, engineer, citizen of Germany, subject of the King of Prussia and Emperor of Germany, residing at Potsdam, Kanal 10, in the Kingdom of Prussia and Empire of Germany, have invented certain new and useful Improvements in Bottle-Closures, of which the following is a full, clear, and exact description.

10 My invention relates to improvements in bottle closures and has for its object, first, to provide a closure adapted to be seated in a bottle neck and to permit the free discharge of any liquid as liquor, cognac, etc., from the 15 filled bottle, but to prevent refilling of same with a liquid of inferior value, when once empty, and second to leave the closure intact in case of breaking the neck of the bottle, after the same having been emptied, rendering thereby the closing device capable of being reused as often as occasion is desired.

20 The present invention consists in a combination and arrangement of parts as hereinafter more fully described, shown in the 25 accompanying drawings and pointed out in the appended claim.

25 The improved invention relates to that class of bottle closures for non re-fillable bottles which are secured in the bottle neck and 30 can only be removed after breaking the neck of the bottle. According to the present invention however, a new result is obtained in that the closure prevents a refilling of the inverted bottle by means of a compressed 35 liquid.

A bottle closure embodying my invention is illustrated in the accompanying drawing in which:

40 Figure 1 is a vertical sectional view of the improved bottle closure. Fig. 2 is a view of the improved bottle closure shown in side elevation mounted in the neck of a bottle shown in vertical section. Fig. 3 is a horizontal sectional view of the improved bottle 45 closure.

45 The special features of the invention lie in the arrangement of the main canals 2, 3, formed in the neck of the bottle, the shorter connecting canals 17, 18 formed in a rigidly seated stopper or plug 6 and converging to a central cavity or cup 11, the canals 17, 18, extending inwardly in the plug 6 and communicating with the channels 2, 3, formed in the bottle neck and the spherical valve 12', having vertical movement or play in the cavity or cup 11. All these canals must have

the same sectional area; the length however, of the canals 2, 3, together with the length of the connecting canals 15, 16 formed in the plug 6 and communicating with the central cavity 11 must be double the length of the second canals 17, 18 which run directly into the hollow cup 11 and meet in the center of the plug.

50 When the bottle is inverted, the valve 12' will fall into the bottom of the cavity 11 which forms a cup to receive it, and will close the opening into said cup from the canals 17, 18, but will be below the inner ends of the channels 15, 16. The contents of the 55 bottle will then flow out through the channels 15, 16—2, 3. The position the valve 12' will take when the bottle has been reversed, is shown by dotted lines (see Fig. 1).

55 Any refilling of the bottle by compressed liquid is now prevented for the reason that the compressed liquid seeks first its way through the short directly running canals 17—18, below the valve 12' pressing it upwardly a little easily beyond the inner ends 70 of the canals 15, 16 as the valve is made of glass or a non-oxidable substance without any great weight; this permits a joining of the streams of compressed liquid through all the 75 canals, thus pressing the valve upward with 80 more force and causing the valve to rest against the seat 13, thereby closing the opening 14 so that no liquid can pass through the 85 opening 14 into the bottle.

85 To secure the plug 6 in place in the neck 90 of the bottle, and allow the contents to be poured out, the plug is formed with a diametrical channel in which are fitted bolts 9, 10, and an intervening spiral spring 8, which presses the bolts outwardly. To receive 95 these bolts the bottle neck is formed with interior segmental, horizontally arranged channels 4—5. When the plug 6 is inserted, these bolts project into the channels 4, 5, and prevent the plug from being withdrawn. 100 The plug however, can be turned around so as to close or open the bottle at will for the outflow of the liquid.

105 The channels 2, 3, communicate with the channels 15, 16—17, 18 only in one position of the plug, as when all the channels lie in the same vertical plane, partially shown in Figs. 1 and 3, and the contents of the bottle can only be poured out when such communication is effected by turning the plug 6. 110 In any other position of the plug the bottle is sealed.

Having thus described the invention, what I claim is:

The combination with a bottle having downwardly extending open sided channels 5 on the interior of its neck, with open ends at the mouth of the bottle, of a rotatable plug having a central cavity in its lower part, and two series of channels communicating therewith, each series communicating with the 10 channels in the bottle neck but at different levels from the other series, whereby the course of travel of liquid from the inlet of the last named channels to the central cavity will be longer through one series than 15 through the other; a spherical valve located

in the cavity, a valve seat in the plug at the lower end of the cavity, the parts being so disposed that when liquid is forced into the said channels while the bottle is inverted it will first press on the lowest part of the 20 valve, and raise the same so as to open all the channels and cause the valve to impinge against its seat and prevent ingress of liquid.

In witness whereof, I subscribe my signature, in presence of two witnesses.

ADOLF DREYER.
